ELECTRICAL PRODUCTION OF LIGHT.

1,110,562.

Specification of Letters Patent.

Patented Sept. 15, 1914.

Original application filed April 11, 1898; Serial No. 877,199. Divided and this application filed May 2, 1912.
Serial No. 694,648.

To all whom it may concern:

Be it known that I, PETER COOPER HEWITT, a citizen of the United States, and resident of Ringwood Manor, county of Passaic, 5 State of New Jersey, have invented certain new and useful Improvements in the Electrical Production of Light, of which the following is a specification:

The object of my invention is to provide 10 a new and useful means of producing light by electricity, whereby a light of high illuminating power is produced, and the intensity and color of the light may be varied.

I have discovered that certain vapors of 15 specific density and physical condition have the property of becoming intensely light radiant when an electric current is passed through them. Such a vapor is the vapor of mercury, sodium, iodin and other metals, 20 each producing a light with colors peculiar to itself. The light giving quality depends chiefly on the density of the vapor, as well as the material, it being most intense at the point of saturation, or boiling point of the 25 metal, the light giving quality being somewhat proportioned to the density. Besides simple metallic vapors, other gases have this property to a certain extent, but most of them are objectionable on account of the 30 temperature necessary, and also on account of the electrical resistance at the point where their vapor is in the physical state, which allows them to be light radiant. For these 35 reasons their use in many cases is impracticable. In the case of mercury, which is a fair example of a metal volatilizing at a 40 practical temperature, and vapor is inclosed or formed in a tube whose ends are turned down so as to hold a globule of mercury, into which are led wires for conducting the 45 electrical current, which wires may be submerged in the volatilizable material or not, as desired. In case the wire or electrode projects through the material to be volatilized, the wire becomes heated on the discharge of 50 an electric current, which in turn heats the material to be volatilized and volatilizes it, filling the tube with its vapor, if the tube is not already of such a temperature that it is 55 not sufficiently full of vapor. It is well known that a wire leading into an attenuated atmosphere becomes heated, although the same sized wire will conduct the current

under ordinary conditions without heating. In the case where the material to be volatilized constitutes the electrode, the current heats the electrode direct, producing the same effect. A tube may be constructed containing an exact amount of vapor (or material to produce the vapor) necessary to 60 produce this intense light electrically, in which case the exact degree of vapor density and physical conditions can be produced which is most advantageous. The electrodes must be made of such size as not to deteriorate by the electrical discharge. The light 65 action of these tubes is intermittent and the electric current impulses or oscillations can be made with the frequency desired, and so rapid as to require a most delicate instrument to detect that the light is no continuous. A tube in the form described, one quarter of an inch in diameter, one foot in length will produce a light too brilliant to 70 look at, the light being more than a hundred 75 candle power. The quantity of light may be varied by the current used, from great brilliancy to the bare luminosity of ordinary vacuum tubes or Geisler tubes. This tube is practically indestructible, having nothing to 80 ruin or destroy, operating at somewhere about a temperature of 300° C., if mercury is used. In the case where other metals or materials are used, my tubes operate at the 85 temperature a little above the boiling point or thereabouts, of the substance in a vacuum. It is advisable to use a substance which volatilizes at ordinary temperatures as near as possible, for economy. The metal rhubidium gives a deeper red light than any other, 90 and I prefer to use this metal or a metal having a deep red band in the spectrum, or a proportion of this metal to obtain a deeper red color in my tubes. Potassium, also lithium give fair results, the temperatures being 95 higher. In practice a more agreeable light will be produced by the judicious use of two or more tubes, each containing different vapors.

In order to more fully explain my invention, reference is had to the accompanying drawing forming a part of the specification, in which similar characters of reference indicate corresponding parts in all the figures.

Figure 1 is a side elevation of one form of 105 a plant for producing the light; Fig. 2 is a

side elevation of a modified form of tube; and Fig. 3 is a longitudinal section of a straight tube having a volatilizable material at one end only.

5 A is an electric generator, B is a converter, C a condenser, D D' wires, terminating in the electrodes E E', extending into the volatilizable substance F, contained in the bulbs G' G² of the vacuum tube G.

10 To operate my light, I use an electric current of varying voltage, having found that from 500 to 5000 volts most successful, but it can be operated at many other electrical pressures, depending on the length of

15 the tube G desired to operate, and the quantity of light to be produced; also for the material used. I place across the wires D D' leading to the tube G the condenser C which is of suitable capacity; the object of the con-

20 denser being to accumulate the electric current during the minute period of time when the current is not passing through the tube G, and deliver the accumulation to the tube G during the time the tube is taking current.

25 The condenser also aids the light giving quality of the tube. This condenser C being in resonance with the tube G and current, will adjust the voltage of the current in some degree to any varying resistance

30 that may occur in the tube. The tube itself is a condenser of certain capacity under the condition that I establish, and under light giving conditions is oscillatory or intermittent, acting somewhat as a discharger for

35 the condenser, producing waves or pulsations in the current from the condenser. The tube G is constructed with the volatile electrodes G' G², and is proportioned in size to the current to be used. The resist-

40 ance of the vapor in a high degree of attenuation is greater than it is when it becomes a little more dense; then becoming more dense the electrical resistance increases so that if the electrodes overheat, the vapor

45 generated will shut off the electric current until they are again sufficiently cool, but with a properly constructed tube, this only happens through accident. At a constant pressure the electrical resistance of vapor decreases as the temperature increases.

In order to produce one of my tubes, I first exhaust it to a high vacuum, hot, then turn on the electric current and while the current is on, cause the absolutely pure

55 vapor to flow through the tube, or generate in the tube and flow into the pump until it has carried away with it all the impurities existing in the tube. When this is accom-

60 plished at the required vapor density (pres- sure and temperature), the fact becomes self-evident by the great quantity of light coming from the tube. The quantity of light is approximately proportional to the vapor density. The quantity of light is

65 under absolute control, electrically or other-

wise. I have found it advantageous, even when operating tubes at almost atmospheric pressure temperature, to prevent radiation of heat to avoid the heat loss. As the vapor in the tube is very attenuated in the case of 70 metals that volatilize above the atmospheric temperature, it may become necessary in the economical use of some of them to use a starting device, to acquire the proper vapor density on starting. Such a starting de- 75 vice may consist of applied or external heat or an increased electrical potential for the time being. I have found in the case of mercury where the tube operates at about 300° C., that by supplying from an out- 80 side source, the heat which otherwise would be radiated from the tube, I have a some- what corresponding increased production of light. These tubes may be made in almost any shape from spirals to straight tubes, or 85 inverted U-shaped tubes, or U-shaped tubes; but in the case of a U-shaped tube used for volatile material.

In order to equalize the pressure within the tube, I may provide the same with a 90 reservoir G³ in communication with the interior of the tube to be filled with vapor, which, however, is not affected by the current and rendered luminous, as the current does not pass through it, and hence the vapor contained therein can act as an equalizer to give the light a uniform brilliancy and steadiness.

Fig. 3 shows a straight tube with a volatilizable substance at the lower end, and a 100 solid piece of iron or the like suspended in the upper enlarged end, electric wires lead- ing to the substance and the piece of iron.

The electrical resistance of varying saturated vapors varies in a very great degree 105 for the same density, mercury vapor being of comparatively low resistance and iodin vapor of high resistance. I prefer to use vapors of low electrical resistance as more economical and convenient. In producing 110 my tubes containing mercury I have found that a very small amount of oxygen or oxid of mercury in the tube increases in a marked degree the electrical resistance and impairs the light radiating quality. I have also 115 found that the combination of two or more tubes, each giving rays of light of a different color, is advantageous.

This application is a division of my ap- 120 plication filed April 11, 1898, Serial Num- ber 677,199.

I claim as my invention:

1. The method of operating gas or vapor electric lamps having a mercury cathode and an anode therein which consists in ap- 125 plying to the electrodes an electric potential exceeding 500 volts per foot of luminous column.

2. The method of operating gas or vapor electric lamps having a mercury cathode 130

and an anode therein, the dimensions of the lamp being approximately 1 foot in length and $\frac{1}{4}$ inch in diameter which consists in applying to the electrodes an electric potential exceeding 500 volts per foot of luminous column.

3. The combination of a vapor electric lamp, comprising an exhausted container, a vaporizable electrode material therein, said lamp operating at a relatively high vapor pressure, and special means for automatically bringing the vapor pressure in said lamp from the low pressure inoperative condition to the high pressure operating condition.

4. The combination of a vapor electric lamp comprising an exhausted container, a vaporizable electrode material therein, said lamp operating at a relatively high vapor pressure, and special means for automatically bringing the vapor pressure in said lamp from the low pressure inoperative condition to the high pressure operating condition, said means comprising a resonating electrostatic capacity connected with the supply circuit to the lamp.

5. The method of operating electric apparatus comprising an hermetically sealed container, a mercury cathode and an anode, said container being exhausted to a high de-

gree of purity which consists in raising the temperature of the cold lamp until the starting resistance falls and then maintaining the tube at a vapor density requiring at least 500 volts per foot of tube.

35

6. The method of operating electric apparatus comprising an hermetically sealed container, a mercury cathode and an anode, said container being exhausted to a high degree of purity which consists in raising the temperature of the cold lamp until the starting resistance falls and requiring a voltage in proportion of at least 500 volts per foot of quarter inch tube.

40

7. The method of operating electric apparatus comprising an hermetically sealed container, a mercury cathode and an anode, said container being exhausted to a high degree of purity which consists in raising the temperature of the cold lamp until the starting resistance falls and maintaining the lamp at the condition requiring at least 500 volts in a quarter inch tube a foot in length.

45
